PERFUME DISPENSER

Steven La Scola, Bloomfield, N. J.

Application August 11, 1949, Serial No. 4,413

Term of patent 14 years

(Cl. D86—10)

To all whom it may concern:

Be it known that I, Steven La Scola, a citizen of the United States, residing at 82 West Passaic Avenue, in the town of Bloomfield, in the county of Essex and State of New Jersey, have invented a new, original, and ornamental Design for a Perfume Dispenser, of which the following is a specification, reference being had to the accompanying drawing, forming part thereof, in which—

Fig. 1 is a side elevational view of a perfume dispenser, showing my new design.

Fig. 2 is a top plan view thereof; and

Fig. 3 is a bottom plan view.

I claim:

The ornamental design for a perfume dispenser, as shown.

STEVEN LA SCOLA.
